UNITED STATES PATENT OFFICE.

CAROLINE MONTEITH, OF SOUTH ORANGE, NEW JERSEY.

JUVENILE PRINTING-BLOCK.

1,340,072.

Specification of Letters Patent. Patented May 11, 1920.

Application filed October 10, 1917. Serial No. 195,835.

To all whom it may concern:

Be it known that I, CAROLINE MONTEITH, a citizen of the United States, and a resident of South Orange, in the county of Essex and State of New Jersey, have invented a new and Improved Juvenile Printing-Block, of which the following is a full, clear, and exact description.

The object of the invention is to provide 10 a new and improved juvenile printing block for teaching children or beginners to read, without the usual formal exercises, by utilizing the natural activities and powers of children as they play and the art of printing their own reading material.

The invention consists of certain novel features of construction as hereinafter shown and described and then specifically pointed out in the claims.

20 A practical embodiment of the invention is represented in the accompanying drawings forming part of this specification, and in which similar characters of reference indicate corresponding parts in all the views.

25 Figure 1 is an end elevation of the improved juvenile printing block;

Fig. 2 is a plan view of the reading face of the juvenile printing block;

Fig. 3 is an inverted plan view of the 30 printing face of the juvenile printing block;

Fig. 4 is a plan view of one of the printing block sections in position for making an impression on a strip of paper held on an impression plate;

35 Fig. 5 is a sectional side elevation of the impression plate and the strip of paper, the section being on the line 5-5 of Fig. 4; and

Fig. 6 is an end view of the printing block 40 section in position on the strip of paper held on the impression plate.

The juvenile printing block 30 is formed of a number of sections 31 having dovetail grooves 32 engaged by correspondingly shaped dovetail tongues 33 to hold the sections 31 in assembled sequence one relative to the other. Each of the sections 31 is provided with a printing face 34 representing a predetermined sentence, and the other

50 face of each section 31 is provided with a reading face 35 of the corresponding sentence appearing on the printing face 34.

In using the printing block the child or beginner disassembles the sections 31 by disconnecting the same from the tongues 33. The beginner now makes a number of im-

pressions, side by side, on a strip of paper 40 of each printing face 34 (see Fig. 4), and while this sheet 40 is drawn through a guideway 41 formed on an impression plate 42 on which rests the strip 40. The strip 40 unwinds from a roll 43 held on a spindle 44 mounted within a suitable casing 45 attached to one end of the impression plate 42. The spindle 44 is provided at one outer 60 end with a knob 46 under the control of the beginner to unwind the strip 40 and to draw the same through the guideway 41 over the impression plate 42. It is understood that while making an impression on the strip 70 40 by one of the sectional blocks 31 the reading face 35 thereof is uppermost, as shown in Figs. 4 and 6, while the printing face 34 is lowermost to make contact with the strip 40.

The child or beginner next assembles the sections 31 by connecting the sections with each other by the tongues 33. The child or beginner now prints by one impression on a sheet or other surface the several sentences, 80 one below the other, in the desired sequence in which the sections are arranged on the printing block.

From the foregoing it will be seen that the child or beginner can readily print single sentences or the same sentences at one impression in a desired sequence, the several sentences preferably pertaining to the same subject.

By the use of the juvenile printing block a 90 child or beginner under the direction of a teacher prepares its own reading material in several different sentences pertaining to a single subject under consideration at the time. Thus the child or beginner reproduces 95 the substance of a story told or of a lesson read and receives the impression that learning to read is for the purpose of gaining knowledge. Incidentally, the impressions of word forms and of correct spelling are confirmed. It is evident that the reproduction of sentences by the use of printing block sections as described is superior to the reproduction by handwriting as heretofore practised.

100 It will also be seen that by the method described the beginner learns to recognize word forms by the eye more easily and in less time than to learn to write word forms with the hand. It is readily perceived that number work (numerals, dots and their combinations) and phonetics (letters and their com-

binations) require the beginner to reproduce the symbols in as distinct and perfect form as is possible and this result can only be accomplished by the use of type.

5 By making impressions with the printing blocks on strips and sheets of paper and pasting the same into a blank book the beginners practically become little printers and book makers.

10 It will further be noticed that the method described can be readily used for teaching foreign languages.

Having thus described my invention, I claim as new and desire to secure by Letters 15 Patent:-

20 1. As an article of manufacture, a juvenile printing block for the use of children to make an impression of a number of sentences relating to one subject and arranged one below the other, the said block comprising a series of printing block sections each provided with a single sentence printing face and a reading face with a like sentence, the printing and reading faces of the several 25 sections pertaining to the same subject, and means detachably connected with and connecting the printing block sections with each

other one below the other and with the reading faces of the several sections uppermost and the printing faces at the bottom, to allow 30 of making a single impression of all the sentences pertaining to a single subject.

2. As an article of manufacture, a juvenile printing block for the use of children to make an impression of a number of sentences 35 relating to one subject and arranged one below the other, the said block comprising a series of printing block sections each provided with a single sentence printing face and a reading face with a like sentence, the 40 printing and reading faces of the several sections pertaining to the same subject, each printing block section being provided at both sides with dovetail grooves and separate dovetail tongues engaging the said 45 grooves to detachably connect the printing block sections with each other and one below the other, the said reading faces being uppermost and the printing faces being at the bottom to allow of making a single impression 50 of all the sentences pertaining to a single subject.

CAROLINE MONTEITH.
